UNITED STATES PATENT OFFICE.

FLORENCE ANNA WOOD, OF WARSAW, INDIANA.

BEDPAN.

Application filed June 24, 1921. Serial No. 420,051.

To all whom it may concern:

Be it known that I, FLORENCE ANNA Wood, a citizen of the United States, and a resident of Warsaw, in the county of Kosciusko and State of Indiana, have invented a new and useful Improvement in Bedpans, of which the following is a full, clear, and exact description.

My invention relates to bed pans, and it 10 consists in the combinations, constructions and arrangements herein described and claimed.

An object of my invention is to provide a bed pan having means at the front end 15 thereof for supporting the legs of a patient and for preventing the overflow or "splashing over" of the contents of the pan, whereby the soiling of the bed clothing is prevented and the necessity for changing the 20 bed clothing each time the pan is used is obviated.

A further object of my invention is to provide a bed pan having a maximum capacity for a pan of given longitudinal and 25 transverse dimensions.

A further object of my invention is to provide a bed pan that is capable of being cleaned thoroughly and easily, since it has no sharp corners or recesses in which sediment 30 may lodge.

A further object of my invention is to provide a bed pan in which a portion of the upper surface thereof is curved to conform 35 with the body of a patient and another portion thereof, which is relatively elevated, is curved to conform with the curvature of the legs of the patient and to provide a rest for the latter.

A further object of my invention is to 40 provide a device of the character described in which a member for supporting the legs of a patient is also formed to provide a spout or "pouring lip" for the device.

Other objects and advantages will appear 45 in the following specification and the novel features of the invention will be particularly pointed out in the appended claims.

My invention is illustrated in the accompanying drawings, forming part of this application, in which—

Figure 1 is a longitudinal section through the device along the line 1—1 of Figure 2,

Figure 2 is a plan view of the device, and

Figure 3 is an end view of the same.

55 In carrying out my invention, I provide a receptacle having a bottom 1, sides 2—2,

a rear end wall 3, a front end wall 4, and an upper wall 5. These parts are made of any suitable material, such as a light metal, waterproofed paper, or the like, and may be 60 formed integrally with one another or separately and joined in any suitable manner to have a liquid tight connection with one another. The receptacle flares laterally in opposite directions adjacent to its rearward 65 end, as best seen in Figure 2. The bottom 1 is therefore wider at its rearward end than at its forward end and the portion of each of the sides 2—2 adjacent to the end 3 is offset, as at 6, with respect to the body 70 portion thereof. The sides 2—2 and the end 3 are inclined as shown, whereby a receptacle of a maximum capacity for a given length and a given width is provided.

The upper wall 5 terminates approximately midway the length of the receptacle and the sides 2—2 are inclined from the points of their junction with the upper wall 5 to the end wall 4 which therefore has a height considerably greater than that of the 80 end wall 3. The end wall 4 is inclined as shown and is formed intermediately to provide an inclined spout or pouring lip 7. Since the upper wall 5 terminates approximately midway the length of the receptacle, 85 an opening 8 extending from the rear edge of upper wall 5 to the end 4 and the entire width of the receptacle is provided. A shield or baffle 9 partially covers the opening 8 and has a liquid tight friction fit with 90 the inclined portions of the sides 2—2 and with the end 4. The upper wall 5 is formed at its rear edge to provide a seat 10 for a cover 11 that is adapted to completely cover the opening 8 and has a liquid tight fit with 95 the shield 9, portions of the sides 2—2, and with the edge of the upper wall 5. The cover 11 has a handle 12 adapted to be grasped by hand, whereby it can be conveniently removed from the receptacle or 100 placed thereon in position to close the opening 8, as illustrated in the drawings.

From the foregoing description of the various parts of the device, the operation thereof may be readily understood. The 105 upper wall 5 is curved to conform with the contour of the body of a patient. The shield 9 is fashioned to provide depressions 13 and 14 curved to receive the legs of the patient and to provide a rest for the legs of the 110 patient. The body of the patient rests upon the upper wall 5 and the legs rest upon the

shield 9 when the pan is being used and consequently no other support is necessary to maintain the patient in position to use the pan. Heretofore, it has been necessary for 5 the nurse or other attendant to support the knees of the patient in many cases. The relatively wide bottom 1 provides a stable base for the receptacle which cannot therefore be readily upset and no strain is placed 10 on the patient in order to remain in position to use the pan.

It is important to note that the shield 9 serves not only as a leg rest but also prevents the splashing over of the liquid from 15 the receptacle at the front end thereof. In all bed pans of which I am aware, more or less splashing or spilling of the liquid from the pan occurs at the front end thereof and in consequence the bed clothing are soiled 20 each time the pan is used. The spilling of liquid from the receptacle embodying my invention is prevented on account of the provision of the shield 9 and on account of the fact that the front end wall 4 and the 25 inclined forward portions of sides 2-2 are relatively high. The end wall 4 aids in supporting the leg rest 9, serves as the front retaining wall of the receptacle, and is formed intermediately as described so that 30 the contents of the receptacle can be poured therefrom when the cover 11 and the shield and leg rest 9 have been removed. The

opening 8 is relatively large and access may therefore be had to the interior of the receptacle, which can therefore be thoroughly 35 and readily cleaned.

I claim:

1. A bed pan comprising a receptacle having a bottom, sides, ends, and an upper wall extending from one end approximately midway to the other end, thereby defining an opening at the upper side of the receptacle, and a removable shield engaging the last named end along its upper edge and the portions of the sides adjacent to the last named 45 end along their upper edges to partially close the opening and to provide a rest for supporting the legs of a patient using the pan, said last named end being formed to provide a pouring lip for the receptacle. 50

2. A bed pan comprising a receptacle having bottom, side and end walls, an upper wall extending from one end approximately midway to the other end wall, and a removable shield covering the forward part 55 of the opening and engaging the last named end wall and the adjacent portions of the side walls along their upper edges, said shield being fashioned to provide substantially parallel depressions extending longitudinally of the receptacle, said depressions being adapted to receive the legs of a patient using the pan. 60

FLORENCE ANNA WOOD.
